UNITED STATES PATENT OFFICE.

THEODORE A. FEDERWITZ AND WALTER T. BAILEY, OF PHILADELPHIA, PENNSYLVANIA, ASSIGNEES TO STOKES AND SMITH COMPANY, OF PHILADELPHIA, PENNSYLVANIA, A CORPORATION OF PENNSYLVANIA.

BOX-COVERING MACHINE.

Application filed April 12, 1924. Serial No. 705,990.

To all whom it may concern:

Be it known that we, THEODORE A. FEDERWITZ and WALTER T. BAILEY, citizens of the United States, residing in the city and county of Philadelphia, State of Pennsylvania, have invented certain new and useful Improvements in Box-Covering Machines, of which the following is a specification.

10 Our invention relates to machines for covering stayed or unstayed boxes, and their covers, by applying thereto cover blanks or wrapper sheets.

In accordance with our invention, the 15 plunger which is connected to and operates the main form block is of tubular structure, within which is disposed and relatively movable the auxiliary plunger structure, connected to and actuating the auxiliary 20 form block; and the aforesaid tubular main plunger is disposed and movable within a tubular sleeve or plunger which carries and actuates the stripper mechanism.

Further in accordance with our invention, 25 we dispense with the weight heretofore commonly used for rebalancing the main form block operating plunger, and apply to that plunger and the plunger which carries the stripping mechanism springs which permit 30 higher speed of operation, and which are so positioned or disposed that they exert on their respective plungers forces whose magnitudes are approximately constant throughout the strokes of the plungers.

35 Further in accordance with our invention, the support or column which carries the mechanism for actuating or controlling the main and auxiliary form blocks and stripper mechanism, whatever their nature or 40 structure, is disposed in effect at a corner of the table or support which carries the mechanisms for actuating the wrapper-applying tools or instrumentalities, whereby more room is afforded for the operator or attendant, and, in addition, makes the wrapping machine unit as a whole utilizable with box- 45 and wrapper sheet-delivering or conveying mechanism.

Further in accordance with our invention, 50 the work-supporting platen is carried by a plunger whose downward movement is opposed by a spring connected, on the one hand, to the machine support or base and on the other hand, to lever structure con-

necting with the plunger and of such construction that the force exerted by the spring in opposition to the downward movement of the platen remains substantially constant throughout the stroke of the platen.

Further in accordance with our invention, 55 the mechanism for ejecting a finished box from the platen is operated and controlled by means connected to and movable in unison with a member which actuates one of the wrapper-applying tools or instrumentalities; 60 and more particularly in accordance with our invention, the ejector mechanism is operated and controlled by a slide which carries a wrapper-applying tool and which is operated and controlled by a cam which actuates and controls one or more additional 65 wrapper-applying tools.

Our invention resides in features of arrangement, location, construction and combination of the character hereinafter described and claimed.

For an illustration of one of the various forms our invention may take, reference is to be had to the accompanying drawings, in which:

Fig. 1 is a side elevational view, partly in vertical section, of apparatus embodying our invention.

Fig. 2 is a top plan view of structure shown in Fig. 1.

Fig. 3 is a vertical sectional view, parts in elevation, on enlarged scale, of plunger structure shown in Fig. 1.

Fig. 4 is a horizontal sectional view, partly in plan, taken on the line 4-4 of Fig. 3.

Fig. 5 is a bottom plan view, partly in horizontal section, on the line 5-5 of Fig. 1.

Fig. 6 is a vertical sectional view, parts in side elevation, on enlarged scale, of the mechanism for controlling and actuating the ejector mechanism.

Referring to Fig. 1, there is shown a box-covering machine in general similar to that shown in our prior application Serial No. 647,012, comprising the base or pedestal 1 carrying the bearing sleeve 2, upon which rotates the worm wheel 3 continuously driven by the worm 4 driven by the continuously rotating shaft 5 driven by any suitable source of power, not shown. Bearing upon the sleeve 2 is the main cam 6, driven by the gear 3 through suitable clutch

mechanism, such as described in the aforesaid application Serial No. 647,012, for effecting successive single revolutions of the cam 6. Secured upon the upper end of the cam 6 is the bevel gear 7, with and by which mesh and are driven the bevel pinions 8 secured upon and driving the shafts 9 having bearings at the upper end of the casing or housing 10, which is carried by the pedestal 1 and which encloses the gear 3, cam 6 and gear 7, and which carries the table 11 which carries the inwardly and outwardly adjustable slide units 12, 12 and the inwardly and outwardly adjustable slide units 13, 13, the latter, as in the aforesaid application, having superposed cams operating different sets of wrapper-applying tools, while each of the former, as indicated in the aforesaid application and herein, comprises a single cam 14, rotatable upon the shaft 15 driven by the gear 16, which is in turn driven by the gear 17 splined upon the aforesaid shaft 9. The cam 14 is provided with the three cam slots 18, 19 and 20, in each of which is disposed a cam follower actuating a tool-carrying slide. In the example illustrated, the cam follower 21 engages in the cam slot 18 and is secured to and actuates the slide 22, which carries the wrapper-applying tool 23, in this instance a roller.

Carried by the housing of the unit 12 is the housing 24, through whose open lower end extends the member 25 secured to and movable with the slide 22, and upon which is adjustable the block 26. Carried by the housing 24 is the shaft 27, upon which is pivoted the lever arm 28, whose movement in counter-clockwise direction, as viewed in Fig. 6, is opposed by the spring 29. Pivoted upon the member 28 is the detent member 30, whose notched detent end 31 co-acts with the aforesaid block 26. Threaded in the housing 24 is the adjustable screw stop 32, with which co-acts the downwardly extending arm 33 upon the member 30, whose counter-clockwise rotation, as viewed in Fig. 6, is opposed by the spring 34. Pivoted concentrically with the member 30 upon the arm 28, but independently thereof, and biased only by gravity, is the hook latch member 35, also co-acting with the block 26.

The member 28 corresponds in general with the member 135 of the ejector mechanism of the aforesaid prior application 647,012, and similarly carries a pin 36 engaging in a circumferential groove in the second or outer barrel or plunger 37, within which is movable the inner barrel or plunger 38, within which is movable the ejector plunger 39 carrying at its end the box-engaging buffer 40, the ejector mechanism 37, 38, 39, 40 corresponding in construction and mode of operation with the ejector mechanism of the aforesaid application.

Carried by the aforesaid bearing sleeve

member 2 is the downwardly extending arcuate guide 41, in which is guided the cylindrical head 42 secured upon the lower end of the plunger rod or tube 43, upon whose upper end is carried the usual platen 44. Pivoted in the head 42 at 45 is the link 46, pivoted at 47 to the inner end of the lever 48 having the hub 49 pivoted upon the shaft 50 carried in the bracket 51 secured to the pedestal 1. Secured to the hub 49 is the downwardly extending lever arm 52, to which is connected at 53 one end of the helical spring 54, whose other end is secured to the member 55 having the adjusting screw 56 carried by the base 1 and utilizable for suitably tensioning the spring 54.

Mounted upon the table 11, at one corner thereof, that is, between adjacent units 12 and 13, is the base 57 of the upstanding support or column 58 having at its upper end 85 the outwardly extending bracket 59 and the inwardly extending bracket 60.

Secured to the inner end of the bracket 60, by bolts 61, is the vertically extending head 62 carrying at its upper and lower ends the cylindrical bushings 63, in which is vertically slidable the tubular plunger 64, in whose lower end is secured the bearing block or plug 65 carrying the rods 66, to which are attached as usual the stripper rods 67. Extending through a vertical slot 68 in the member 62 is the pin 69, secured to the plunger 64 and provided with a roller 70 which rolls upon the vertically extending guides 71 carried by the member 62. Pivoted upon the pin 69 is one end of the link 72 pivoted at 73 to the lever arm 74, pivoted to the bracket 59 at 75 and having the rearward extension 76, to which is connected at 77 one end of a helical spring 78, whose other end is connected to the column 58, the longitudinal axis of the spring being such with respect to the arm or extension 76 that the force exerted by the spring upon the plunger 64 throughout its movement is approximately constant. Pivoted to the arm 74 at 79 is the downwardly extending rod 80, pivoted at its lower end to the lever 81 pivoted to the casing 1 at 82 and having at its inner end a cam follower engaging in the slot 83 in the main cam 6.

Within the upper end of the tubular member or plunger 64 is secured a bearing bushing 84. Vertically movable within the bearing members 65 and 84 is the tubular plunger 85, within whose lower end is secured the plug or block 86, to which is attached the spur 87 secured at its lower end to the main form block 88. The upper end of the tubular plunger 85 is closed by the plug or block 89, with which co-acts the plate 90, to which are secured the upper ends of the plunger rods 91, 91, which extend downwardly within the tubular plunger 85 and through its lower plug 86 and are attached to the auxili-

ary form block 92. Secured to but adjustable with respect to the plate 90 is the bolt 93, extending freely through the plug 89 and through the helical spring 94 confined 5 between the lower head of the bolt 93 and the plug 89, the spring 94 acting to cause the auxiliary form block 92 to follow and engage the main form block 88.

Within the plunger 85 is the block or plug 10 95, to which is secured the pin 96 extending through the slot 97 in the member 62 and carrying the roller 98 guided by the vertically extending guide members 99. Pivoted upon the pin 96 is the upper end of an adjustable link 100, pivoted at 101 to the lever arm 102 pivoted to the bracket 59 at 75 and having the rearwardly extending arm 103, to which is connected one end of the helical spring 104, whose other end is connected at 15 105 to the column 58 in such position that the longitudinal axis of the spring 104 is so disposed with respect to the arm 103 that the force exerted by spring 104 upon the plunger 85 is substantially constant throughout its 20 movement.

Pivoted to the arm 102 at 106 is the downwardly extending rod 107 pivoted at 108 to the lever 109 pivoted to the housing 1 at 110 and carrying at its inner end a cam follower 30 engaging in the slot 111 of the main cam 6.

The operation of the ejector mechanism is as follows:

For each revolution of the main cam 6 the cam 14 makes one revolution, carrying the slide 22 forwardly and backwardly once for each box-covering cycle. As viewed in Fig. 6, the slide 22 is at its extreme forward position, corresponding with the position and time of rest of the main cam 6 when unclutched from the worm gear 3. Upon re-clutching of the cam 6 to the gear 3 the mechanism starts a new cycle, and during the first part of the cycle the slide 22 remains in its forward position indicated. 40 Later it is withdrawn toward the right by the follower 21 in slot 18, thereby carrying the block 26 toward the right, the spring 29 having previously drawn the ejector members 37, 38 and 39 toward the right as a 45 unit. To ensure that the ejector mechanism be withdrawn sufficiently far toward the right, the hook latch 35 is provided, the block 26 engaging it and rotating the lever 28 in clockwise direction until the limit of 50 travel of the slide 22 toward the right. In so moving in clockwise direction the pin 36, after the barrel 38 has come to rest in the 55 position indicated, because of the engagement of its portion 38a with the housing 24, carries the barrel 37 still further to the right, thereby causing the member 39 to be latched to the member 38. When the block 26 comes into engagement with the hook latch 35, the spring 34 rotates the 60 65 member 30 in clockwise direction, causing its

notch 31 to engage the left side of the block 26. Thereafter the cam 14 moves the slide 22 toward the left, carrying the block 26 toward the left and thereby thrusting through the member 30 against the lever 28, 70 carrying it in opposition to spring 29 in counterclockwise direction, in so doing carrying the pin 36 toward the left until the shoulder 38b on the member 38 engages the inner wall of the housing 24; thereafter the 75 pin 36 moves the barrel 37 still further toward the left, compressing the spring 29 therein until the member 39 is tripped loose from the member 38, whereupon the spring so previously compressed moves the member 39 toward the left, thereby ejecting a finished box from the platen 44. As the slide 22 approaches the limit of its movement toward the left, the detent arm 33 engages the abutment 32, causing withdrawal of the 80 detent 31 from the block 26, thereby freeing the lever 28, which is thereupon quickly drawn in clockwise direction, by spring 29, returning the ejector mechanism to the position indicated.

Inasmuch as the housing 24 and the ejector mechanism carried thereby is movable with the slide unit 12, when the latter is moved inwardly to accommodate smaller boxes or outwardly to accommodate larger 90 boxes to be covered, the ejector mechanism moves therewith and is always in proper adjustment for ejecting boxes from the platen 44, thereby avoiding necessity for structure for adjusting the length of the member 39. 100

The platen 44, as heretofore commonly the case in machines of this type, moves downwardly and returns upwardly, completing one cycle for each cycle of operation of the form blocks 88 and 92, that is, for one cycle 105 of the cam 6. Heretofore it has been customary to oppose downward movement of the platen 44 by a long helical spring disposed within its tubular support, with the result that the resistance offered to downward movement of the platen 44 increased as its downward movement progressed. By the structure herein described, however, the force opposed by the spring 54 to the platen 44 in its downward movement remains for 110 the purposes in mind practically constant, the spring 54 being placed under tension or elongated as the platen 44 descends, and when pressure upon the platen is removed the spring 54 in contracting moves the 115 platen 44 upwardly, the upward movement being limited by the stop 48a, against which the lever engages.

The movements of the tubular plunger 64, 120 the tubular plunger 85, and the plunger rods 91 relative to each other are substantially those well understood in the art in connection with machines of this general type and such as generally disclosed in prior patent 125 to Smith No. 691,329 as regards the form 130

blocks 88, 92 and stripper rods 67, and are operated through one complete cycle for one complete revolution or cycle of operation of the main cam 6, as described in our aforesaid prior application Serial No. 647,012.

However, by the novel structure herein described with respect to these plungers, the bearing bushing 65, moving downwardly with its supporting plunger 64, forms a lateral support and guide structure for both the inner plunger 85 and the plunger rods 91 as they descend. Furthermore, the plunger rods 91, 91 are now disposed within the plunger 85, and this latter is now movable longitudinally within the tubular plunger 64. Furthermore the outer plunger 64 is by the structure described guided in bearings, such as bushings 63, 63, where heretofore the plunger corresponding with plunger 64 has comprised rods guided in bearings, in the present instance the plunger being tubular, and in addition encloses the aforementioned plunger rods 91, 91.

Furthermore, the guide plates 71 and 99, co-acting, respectively, with the pins 69 and 96 through the rollers 70 and 98, respectively, serve to maintain the plungers 64 and 85, and therefore 91, 91, in fixed angular positions with respect to the member 62 and with respect to each other, whereby the form blocks 88 and 92 remain in proper and fixed angular relation with respect to the wrapper-applying tools, including 23, and with respect to the platen 44. And similarly, the member 48 and link 46 prevent rotation of the plunger 43, which carries the platen 44, thereby holding the latter in fixed angular position corresponding with that of the form blocks 88 and 92.

By utilization of the springs 78 and 104, for controlling and opposing movements of the levers 74 and 102 by their operating rods 80 and 107, the inertia of the moving plunger structure as a whole is materially reduced, permitting its higher speed operation; and furthermore, the mode of operation of the springs 78 and 104 is such as to maintain the controlling forces exerted by them substantially constant throughout the movements of the plungers to which they are applied.

As shown in Figs. 2 and 4, the brackets 59 and 60, and lever arms 74 and 102, extend diagonally over the table 11 and diagonally with respect to the form blocks 88, 92 and platen 44, thereby affording extra room for the attendant or operator in reaching for the box and wrapper blanks and placing them in register with each other and then upon the form blocks 88 and 92.

Furthermore, by so locating the column or standard 58, the distance apart between the vertically extending operating rods 80 and 107 is reduced, thereby permitting the use of substantially straight levers 74 and

102, in lieu of offset levers. Furthermore, by locating the standard 58 as described, it permits application to the box-wrapping machine of a box- and wrapper-delivering mechanism which, as described in our prior application Serial No. 698,841, extends over and above the slide units 12 and 13 to a position extending beyond the platen 44; and particularly is such location of the standard 58 of advantage when, as described in the aforesaid application, the box- and wrapper-delivering unit or mechanism partakes of different widths to accommodate different sizes of boxes. As viewed in Fig. 2, the box- and blank-delivering mechanism would extend from below Fig. 2 to a position adjacent the unit 13 at the upper side of Fig. 2.

What we claim is:

1. In a box-covering machine, a longitudinally movable hollow plunger, a second plunger within and movable longitudinally with respect to said first named plunger, and a form block carried by said second named plunger.

2. In a box-carrying machine, a longitudinally movable hollow plunger, a second plunger within and movable longitudinally with respect to said first named plunger, a form block carried by said second named plunger, and stripping mechanism carried by said first named plunger.

3. In a box-covering machine, a longitudinally movable hollow plunger, a second plunger within and movable longitudinally with respect to said first named plunger, a bearing for said second named plunger on said first named plunger adjacent one end thereof, and a form block carried by said second named plunger.

4. In a box-covering machine, a longitudinally movable hollow plunger, a second plunger within and movable longitudinally with respect to said first named plunger, a bearing for said second named plunger on said first named plunger adjacent one end thereof, a form block carried by said second named plunger, and stripper mechanism carried by said bearing.

5. In a box-covering machine, a longitudinally movable hollow plunger, a second plunger within and movable longitudinally with respect to said first named plunger, a form block carried by said second named plunger, a second form block, and plunger structure attached thereto and disposed within and movable longitudinally independently of said second named plunger.

6. In a box-covering machine, a longitudinally movable hollow plunger, a second plunger within and movable longitudinally with respect to said first named plunger, a form block carried by said second named plunger, a second form block, plunger structure attached thereto and disposed within and movable longitudinally independently

of said second named plunger, and stripper mechanism carried by said first named plunger.

7. In a box-covering machine, the combination with a longitudinally movable plunger, of a form block attached thereto, a second form block, and plunger structure attached to said second form block and disposed within and movable longitudinally 10 with respect to said first named plunger.

8. In a box-covering machine, the combination with a longitudinally movable hollow plunger, of a member carried thereby and disposed in one end thereof, a form 15 block attached to said member, a second form block, and plunger rods connected to said second form block and extending through said member into said hollow plunger and movable longitudinally 20 with respect thereto.

9. In a box-covering machine, the combination with a head, of a hollow plunger movable longitudinally with respect to said head, said head having a longitudinally extending slot, a member extending through 25 said slot and secured to said plunger for moving it, a second plunger disposed within and movable longitudinally with respect to said first named plunger, and a form block 30 carried by said second named plunger.

10. In a box-covering machine, the combination with a head, of a hollow plunger movable longitudinally with respect to said head, said head having a longitudinally extending slot, a member extending through 35 said slot and secured to said plunger for moving it, a second plunger disposed within and movable longitudinally with respect to said first named plunger, a form block 40 carried by said second named plunger, said first named plunger and said head having registering longitudinally extending slots, and a member extending through said slots, and secured to said second named plunger 45 for moving it.

11. In a box-covering machine, the combination with a head having a longitudinally extending slot, of guide members secured to said head on opposite sides of said slot, a plunger disposed within and movable longitudinally with respect to said head, a member extending through said slot and secured to said plunger for moving it, and a roller on said member co-acting with said 55 guide members.

12. In a box-covering machine, the combination with a head having a longitudinally extending slot, of a hollow plunger movable longitudinally with respect to said head and having a slot registering with said first named slot, a second plunger within and movable with respect to said plunger, a member extending through said slots and secured to said second named plunger for moving it, guide members on said head on 60

opposite sides of said slot therein, and a roller on said member co-acting with said guide members.

13. In a box-covering machine, the combination with a longitudinally movable 70 plunger, of stripping mechanism carried thereby, a pivoted lever for actuating said plunger, means for actuating said lever, and a spring acting upon said lever in such direction and at such position on said lever 75 that the force exerted thereon by said spring is approximately constant throughout the movement of said plunger.

14. In a box-covering machine, the combination with a longitudinally movable 80 plunger, of a form block carried thereby, a pivoted lever for actuating said plunger, means for actuating said lever, and a spring acting upon said lever in such direction and at such position on said lever 85 that the force exerted thereon by said spring is approximately constant throughout the movement of said plunger.

15. In a box-covering machine, a work-supporting platen, a longitudinally movable 90 support for said platen, a spring opposing movement of said support, and a mechanical movement connected between said spring and said support, said spring and mechanical movement being so disposed and related 95 that the force exerted by said spring upon said support is approximately constant throughout the longitudinal movement of said support.

16. In a box-covering machine, a work-supporting platen, a longitudinally movable support for said platen, a spring opposing movement of said support, a pivoted lever connected to said spring, and a link pivoted 100 to said lever and to said support, said spring, lever and link being so disposed that the force exerted by said spring upon said support in opposition thereto is approximately constant throughout the longitudinal 105 movement of said support.

17. In a box-covering machine, the combination with a work-supporting platen, of a vertically movable supporting column therefor, a bearing sleeve through which said column is guided, a cylindrical head 110 on the end of said column opposite to said platen, an arcuate guide for said head carried by said bearing sleeve, a base supporting said bearing sleeve, a lever pivoted upon said base, a spring connected to said 115 lever and to said base, and a link pivoted 120 to said lever and said head.

18. In a box-covering machine, the combination with a support of a plurality of cover-applying mechanisms adjustable on 125 said support in paths at right angles to each other, an upstanding column disposed between said paths, and form-block-operating mechanism carried by said column.

19. In a box-covering machine, the com- 130

- 15 bination with a table, of a plurality of slide units carried by said table and adjustable thereon in paths at right angles to each other, cover-applying tools controlled by said slide units, an upstanding column disposed adjacent a corner of said table between said paths, form block plunger structure carried by said column, and means carried by said column for actuating said 10 plunger structure extending over said table at an angle to said paths.
- 20 20. In a box-covering machine, the combination with an upstanding column, a head carried thereby, form block structure, plunger structure for operating the same carried by and movable with respect to said head, and means for actuating said plunger structure extending from said column diagonally of said form block structure.
- 25 21. In a box-covering machine, the combination with a support, of wrapper-applying mechanisms carried thereby and adjustable thereon in paths substantially at right angles to each other, an upstanding column disposed between said paths and having an inwardly extending bracket at the upper end thereof, rectangular form block structure, and a member carried by said column for actuating said form block structure extending at a great angle with respect to said paths and the sides of said form block structure.
- 30 22. In a box-covering machine, an ejector, a cover-applying tool, a member for actuating said tool, and means actuated by said member for actuating and controlling said ejector.
- 35 23. In a box-covering machine, an ejector, a box-covering tool, a reciprocating slide carrying said tool, and means actuated by said slide for controlling said ejector.
- 40 24. In a box-covering machine, an ejector, a reciprocating slide, a box-covering tool carried by said slide, a cam controlling said slide, and means carried by said slide for controlling and actuating said ejector.
- 45 25. In a box-covering machine, an ejector, a cam, a plurality of tool-actuating slides actuated by said cam, and means attached to one of said slides for actuating and controlling said ejector.
- 50 26. In a box-covering machine, a slide unit comprising tool-actuating members and means for actuating said members, an ejector carried by said unit, and means actuated by one of said members for controlling said ejector.
- 55 27. In a box-covering machine, an ejector, a tool-actuating slide, a member for actuating and controlling said ejector, a second member carried by said slide, and means effecting a detachable operating connection between said members.
- 60 28. In a box-covering machine, an ejector, a tool-actuating slide, a member for actuating and controlling said ejector, a second member carried by said slide, means effecting a detachable operating connection between said members, and a spring opposing movement of said first named member by 70 said second named member.
- 65 29. In a box-covering machine, an ejector, a tool-actuating slide, a member for actuating and controlling said ejector, a second member carried by said slide, means effecting a detachable operating connection between said members, and means actuating said detachable connection after predetermined movement of said first named member to disconnect it from said second named member.
- 75 30. In a box-covering machine, an ejector, a tool-actuating slide, a member for actuating and controlling said ejector, a second member carried by said slide, means effecting a detachable operating connection between said members, means actuating said detachable connection after predetermined movement of said first named member to disconnect it from said second named member, and a spring for returning said first named member to position from which actuated by said second named member.
- 80 31. In a box-covering machine, an ejector, a tool-actuating slide, a member for actuating and controlling said ejector, a second member carried by said slide, means effecting a detachable operating connection between said members for effecting movement of said first named member, and a member detachably connecting said first and second named members for returning said first named member after movement by said detachable connection.
- 85 32. In a box-covering machine, an ejector, a pivoted lever for actuating and controlling said ejector, a tool-actuating slide, a member movable with said slide, and a second member pivoted on said lever and detachably engaged by said first named member for actuating said lever in one direction.
- 90 33. In a box-covering machine, an ejector, a pivoted lever for actuating and controlling said ejector, a tool-actuating slide, a member movable with said slide, a second member pivoted on said lever and detachably engaged by said first named member for actuating said lever in one direction, and an abutment engaged by said second member to disengage it from said first named member after predetermined movement of said lever.
- 95 34. In a box-covering machine, an ejector, a pivoted lever for actuating and controlling said ejector, a tool-operating slide, a member carried thereby, a detachable connection between said member and lever for operating said lever in one direction, and a member pivoted on said lever and adapted to be engaged by said first named member for returning said lever.

35. In a box-covering machine, a housing, an ejector carried by and movable with respect to said housing, a tool-operating slide movable with respect to said housing, a member disposed within said housing for actuating and controlling said ejector, a second member carried by said slide and disposed in said housing, and means forming an operating connection between said members. 60
36. In a box-covering machine, a slide unit comprising a housing, a cam therein, a tool-operating slide within said housing and operated by said cam, a second housing carried by said first named housing, an ejector carried by and movable with respect to said second housing, a member carried by said slide, and mechanism within said second housing actuated by said member and actuating said ejector. 65
37. In a box-covering machine, the combination with a support, of a unit adjustable to different positions with respect thereto and comprising a tool and means for actuating said tool, and box-ejecting mechanism carried by said unit. 70
38. In a box-covering machine, the combination with a support, of a unit adjustable to different positions with respect thereto and comprising a tool and a member for actuating said tool, and box-ejecting mechanism carried by said unit and controlled by said tool-actuating member. 75
39. In a box-covering machine, the combination with a support, of a plurality of cover-applying units disposed at right angles to each other and adjustable to different positions on said support, an upstanding column disposed between said units, form-block-operating mechanism carried by said column, and box-ejecting mechanism carried by one of said units. 80
40. In a box-covering machine, the combination with a support, of a plurality of cover-applying units disposed at right angles to each other and adjustable to different positions on said support, an upstanding column disposed between said units, form-block-operating mechanism carried by said column, and box-ejecting mechanism carried by one of said units and operable to eject a box past said column. 85
41. In a box-covering machine, a longitudinally movable tubular plunger, a second plunger within and movable longitudinally with respect to said first named plunger, and a form block carried by one of said plungers. 90
42. In a box-covering machine, a longitudinally movable tubular plunger, a second tubular plunger within and movable longitudinally with respect to said first named plunger, a plunger disposed within and movable with respect to said second named plunger, and a form block carried by one of said plungers. 95
43. In a box-covering machine, a longitudinally movable tubular plunger, a second tubular plunger within and movable longitudinally with respect to said first named plunger, a plunger disposed within and movable with respect to said second named plunger, and a form block carried by each of said second and third named plungers. 100
44. In a box-covering machine, a longitudinally movable tubular plunger, a second tubular plunger within and movable longitudinally with respect to said first named plunger, a plunger disposed within and movable with respect to said second named plunger, a form block carried by each of said second and third named plungers, and stripper mechanism carried by said first named plunger. 105
45. In a box-covering machine, a longitudinally movable plunger, a second plunger movable longitudinally with respect to said first named plunger to position beyond said first named plunger, a bearing for said second named plunger on said first named plunger adjacent the end thereof beyond which said second named plunger extends, and a form block carried by one of said plungers. 110
46. In a box-covering machine, a longitudinally movable plunger, a second plunger movable longitudinally with respect to said first named plunger to position beyond said first named plunger, a bearing for said second named plunger on said first named plunger adjacent the end thereof beyond which said second named plunger extends, and a form block carried by said second named plunger. 115
47. In a box-covering machine, a longitudinally movable plunger, a second plunger movable longitudinally with respect to said first named plunger to position beyond said first named plunger, a bearing for said second named plunger on said first named plunger adjacent the end thereof beyond which said second named plunger extends, a form block carried by said second named plunger, and stripping mechanism carried by said first named plunger. 120
